UNITED STATES PATENT OFFICE.

BYRON H. ROSE, OF ROCHESTER, NEW YORK, ASSIGNOR TO THE PULLMAN SASH BALANCE COMPANY, OF SAME PLACE.

SASH-BALANCE.

SPECIFICATION forming part of Letters Patent No. 474,329, dated May 3, 1892.

Application filed March 12, 1892. Serial No. 424,630. (No model.)

To all whom it may concern:

Be it known that I, BYRON H. ROSE, of Rochester, in the county of Monroe and State of New York, have invented a certain new and useful Improvement in Sash-Balances; and I do hereby declare that the following is a full, clear, and exact description of the same, reference being had to the drawings accompanying this specification.

10 My improvement relates to spring-balances for holding sash; and it consists in the combination of a case provided with two side plates, a spring-drum turning on a rivet between the side plates, a loose rim or cover enclosing the spring-drum, and a spring placed between one of the side plates and the cover, whereby the latter is forced against the drum to produce brake action, as hereinafter more fully described.

20 In the drawings, Figure 1 is a perspective view of the device. Fig. 2 is a longitudinal vertical section of the same. Fig. 3 is a cross-section in line $x x$ of Fig. 2.

A indicates the case. It consists of a face-plate a and two side plates b , the latter inclosing the spring-drum and cover.

B is the spring-drum, on which winds the tape C, attached to the sash. The drum is operated by a central coiled spring D, as usual.

30 The drum consists of a cylindrical face c on which the tape winds and a projecting vertical rim or flange d , which extends outward some distance from the face, as shown in the cross-section, Fig. 3.

35 E is the loose rim or cover which incloses the drum. It consists of a shell similar in form to the drum and resting loosely between the two side plates b of the case. Its outer side is circular; but its inner ends $f f$ are straight and tangential and extend clear back to the face-place of the case, by which means it entirely incloses the interior parts. The inner ends of both the drum and cover are open, as shown, and the edge g of the cover 40 bears against the rim d of the drum. Each

part has a hollow interior hub h , which rests on the rivet k , that extends from side to side through the case. By this means both parts are held in position. The driving-spring D is attached at one end to the hub of the cover 50 E and at the other to the face of the drum B, and since the cover is non-revolving the spring is wound up by the turning of the drum.

G is a flat spring interposed between the exterior closed face of the cover E and the 55 side plate b of the case A. It exerts pressure against the cover and forces the face of the latter against the rim d of the drum, thus producing the necessary brake action. The pressure of the spring is gaged at the time the rivet 60 is fastened in place and requires no adjustment afterward, thus presenting great advantages over those devices where the brake has to be tightened up by a screw or other means after the parts are put together. 65

The part E serves the double purpose of a cover to inclose and hide the winding-drum and as a brake to the same, and being loose and unfastened, except by the rivet, it is readily pressed up to place by the spring. 70

Having described my invention, what I claim as new, and desire to secure by Letters Patent, is—

In a sash-balance, the combination of the case A, provided with the side plates b , the 75 spring-drum B, turning on a rivet therein and provided with the projecting rim d , the cover E, fitted loosely between the side plates, inclosing the drum and resting against its rim d , and the spring G, interposed between the 80 cover and the side plate of the case for forcing the cover against the rim of the drum, as herein shown and described.

In witness whereof I have hereunto signed my name in the presence of two subscribing 85 witnesses.

B. H. ROSE.
